UNITED STATES PATENT OFFICE.

ABRAHAM L. BUSCHMAN, OF NEW YORK, N. Y.

PLURAL LAMP SOCKET.

Application filed January 10, 1925. Serial No. 1,545.

To all whom it may concern:

Be it known that I, ABRAHAM L. BUSCHMAN, a citizen of the United States, residing in the city, county, and State of New York, have invented an Improvement in Plural Lamp Sockets, of which the following is a specification.

The present invention relates to an improvement in plural lamp sockets, one object being to reduce the number of parts and simplify manufacturing and assembling operations without detracting from the effectiveness of the device for its intended purpose.

One embodiment of my invention is illustrated in the accompanying drawings in which

Figure 1 is a central longitudinal section,

Figure 2, a side elevation with parts broken away,

Figure 3, a detail view in perspective of a lamp receiving shell, and

Figure 4, a detail in perspective of an insulating washer.

The form of lamp socket shown in the drawings includes a base 1 of porcelain or other suitable insulating material, preferably capable of being formed when in a plastic state. At one end of the base 1 is a plug 2, while the opposite end provides a housing for connected shell receiving recesses, 3 and 4. Passageways 5 and 6 extend longitudinally through the base from said recesses toward the plug 2, their exterior ends opening adjacent to the base of said plug. A central opening 7 receives a bolt 8 which retains a contact or terminal washer 9 at its outer end and supports a twin contact piece 10 at its inner end.

Each recess houses a threaded lamp receiving shell 11 which is preferably formed with a lamp receiving opening at one end and a connector 12 at the other or inner end, said connector being integral with said shell and made of material punched out or displaced from the normal contour of the walls thereof.

The outer end of plug 2 is formed with a recess 13, cooperating with a cap 14 having a central opening and adapted to retain a threaded contact 15 in operative position on the plug 2.

In assembling, the shells 11 are inserted in their respective recesses with the connectors 12 extending through the passageways 5 and 6 respectively. The free end

of each connector is then bent back upon itself and over a detent or key 16 which is preferably a flexible strip of metal such as brass, and is positioned with its ends resting at either side of the outer end of the corresponding passageway, thus in effect spanning the passageway and preventing the connector 12 from moving inwardly toward the shell recess. Channels 17 are molded in opposite sides of the plug 2 and form in effect continuations of the passageways 5 and 6 respectively. When the free ends of the connectors 12 are bent over the keys 16 toward the plug 2, the channels 17 provide space to accommodate the extra thickness of metal thus produced at this point.

After the connectors are anchored or secured in position as described, the threaded contact 15 is slipped down on the plug 2 and into contact with the ends of the connectors 12 where it is secured in part by means of a suitable adhesive, such as a porcelain cement. The shells 11 may also be more firmly fixed in position by applying a similar cement between their exterior surfaces and contiguous surfaces of the recesses 3 and 4.

The threaded contact 15 is further secured in operative position by means of the insulating cap 14 through which is passed the bolt 8.

Fiber or other suitable insulating washers 18 are positioned in contact with the inner ends of the shells 11 being retained in place by means of the twin contact piece 10, the respective arms of which extend through slots 19 in the washer 18.

From the foregoing description it will be apparent that my improved plural lamp socket construction makes it possible to supply an effective device for the intended purpose, yet one in which the number of different parts is kept down to a minimum. It is further clear that the matter of assembling the parts takes a very short time, there being no soldering required and only one bolt assembly. These factors of simplicity make it possible to produce a high grade fixture at a reasonable cost.

I claim as my invention:

1. In a plural lamp socket, the combination of an insulating base comprising a hollow portion having shell receiving recesses and a plug integral with said hollow portion, connector receiving passageways in

said base each communicating with one of said recesses and extending therefrom toward said plug, a threaded lamp receiving shell in each recess, a threaded contact on 5 the plug and a connector in each passageway between said contact and each shell consisting of an integral portion of said shell displaced from material forming a wall thereof and having its free end 10 cured in operative position between said contact and said plug.

2. In a plural lamp socket, the combination of an insulating base having a plug at one end, interconnected shell receiving 15 recesses at the other end, and connector receiving passageways each communicating with one of said recesses and extending

therefrom toward said plug, a threaded lamp receiving shell in each recess, a threaded contact on the plug, and a connector in 20 each passageway between said contact and each shell consisting of an integral portion of said shell displaced from the material forming a wall thereof and having its free end extending beyond the outer end of said 25 passageway, and a detent disposed across said passageway and engaging said free end to retain the connector in contact engaging position.

In testimony whereof, I have signed my 30 name to this specification this 2nd day of January, 1925.

ABRAHAM L. BUSCHMAN.
